CLAIM

The ornamental design for a television receiver, as shown and described.

DESCRIPTION

1. Television receiver

1.1 : Perspective view of a television receiver shown in a first configuration where the display screen is hidden in the stand

1.2 : Front view thereof

1.3 : Back view thereof

1.4 : Left view thereof

1.5 : Right view thereof

1.6 : Top view thereof

1.7 : Bottom view thereof

1.8 : Perspective view of the television receiver shown in a second configuration where the display screen is fully extended

1.9 : Front view thereof

1.10 : Back view thereof

1.11 : Left view thereof

1.12 : Right view thereof

1.13 : Top view thereof

1.14 : Bottom view thereof

1.15 : Perspective view of the television receiver shown in a third configuration where the display screen is partially extended

The present design is a television receiver in which a screen is completely hidden in a stand through a rollable display when a user does not watch content; the broken lines indicate portions of the article that form no part of the claimed design; fig. 1.1 to fig. 1.7 are views showing that a display screen comes into the stand; fig. 1.8 to fig. 1.14 are

(Continued)

views showing that the display screen comes out completely; fig. 1.15 is a view showing that a display panel comes out partially.
